United States Patent Office

Des. 183,781
Patented Oct. 21, 1958

183,781

AUTOMOBILE

Karl Wilfert, Stuttgart-Degerloch, Germany, assignor to
Daimler-Benz Aktiengesellschaft, Stuttgart-Unterturk-
heim, Germany

Application May 4, 1956, Serial No. 41,351

Claims priority, application Germany November 18, 1955

Term of patent 14 years

(Cl. D14—3)

FIG. 3.

FIG. 4.

Figure 1 is a rear view of an automobile embodying my new design,

Figure 2 is a partial plan view of Figure 1,

Figure 3 is a side elevation of the automobile of Figure 1 on reduced scale, and

Figure 4 is an enlarged partial side elevation of Figure 3.

The dominant features of the automobile design in accordance with the present invention are shown in full lines in the drawing. The sides and the front of the automobile not shown are conventional.

I claim:

The ornamental design for an automobile, substantially as shown and described.
